UNITED STATES PATENT OFFICE

OTTO J. GINGERICH, OF TRENTON, OHIO

INTERNAL COMBUSTION ENGINE

Application filed June 1, 1929. Serial No. 367,685.

This invention relates to internal-combustion engines of the Otto type, commonly referred to as the four-stroke-cycle type. In an engine of this type the cycle of a given 5 piston includes, (1) a suction stroke, (2) a compression stroke, (3) a power stroke, and (4) an exhaust stroke.

One object of my invention is to increase the amount of power obtained from expenditure of fuel. Another object is to reduce the 10 deposit of carbon, and another to protect the piston rings from heat.

I shall now describe my improved engine with the assistance of the accompanying 15 drawing, in which

Fig. 1 is a longitudinal sectional view of a cylinder and piston embodying my invention. For convenience it will be assumed that the piston moves vertically, and that in 20 this view it is at the upper end of its stroke;

Fig. 2 is a view looking downward on the end of the cylinder, portions of the valve actuating mechanism having been removed, and

Fig. 3 is an elevational sectional view of the 25 cylinder and piston, showing the piston at nearly if not quite the bottom of its stroke.

The cylinder is indicated by the numeral 10, and the head is bolted to the cylinder in the usual way. The cylinder head comprises 30 a flat plate 11, from which a member 12 extends into the cylinder. For lack of a better name I shall call this member 12 a "column". The piston is a composite structure, one part of which is a deep cup, having a 35 bottom 15 and wall 16. This cup is secured to member 17, which is the piston proper, having the usual packing rings 18-18 and carrying the usual wrist pin 19, connecting the piston to the pitman 20, of which a small 40 portion is seen in Fig. 1. The bottom 15 of the cup rests on the top of the member 17, with a piece of heat-insulating material 21 interposed, a cap screw 22 securing the parts 45 together. The cup serves as a guide for the piston in the cylinder.

As is well known, the conductivity of heat from one part to another of a mass of metal is very much lower where the heat must 50 cross a joint in the metal, than where the

metal is all in one piece. This is true even if the parts are in close contact. For this reason comparatively little heat is communicated from the wall of the cup to the cylinder wall. The wall of the cup shields from the heat of the flaming gas a zone of the cylinder equal in length to the altitude of the cup. This, coupled with the fact that much heat is dissipated by the ribs on the outside of the cylinder (or by a water jacket), prevents the cylinder heating in the neighborhood of the packing rings. Thus the rings are kept cool. As is well known, loss of compression is due to overheated rings. Thus by keeping the rings cool the engine is made to operate at the contemplated compression. Another advantage of cool rings is that less oil is allowed to pass to the cylinder, and thereby the formation of carbon is reduced.

Referring to Fig. 1, it will be observed that there is but little space between the apex of the column and the bottom of the cup. In fact it is but little more than a safe clearance. It results that at the end of the compression stroke of the piston most of the fuel mixture is compressed into the annular space 25 between the column 12 and the cylinder wall. For this reason, and for lack of a better name, I call this space 25 the compression chamber. In the apex of the column, and opening into the above mentioned clearance space 26, is a fuel inlet valve 27. This valve has a stem 28 that passes through the cylinder head, between which and adjusting nuts screwed on the end of the stem is a compression spring 29. Above the valve 27 a chamber 30 is formed in the column, with which chamber a pipe 31 connects. An explosive mixture of fuel and air is supplied to the pipe 31 through a carburetor or any other of the well known fuel supply devices. If the engine has a plurality of cylinders the pipe 31 may tap a fuel manifold. All of this being well understood and in common practice it is needless to illustrate or describe it in detail. For the purpose of cooling the column 12 ventilating pockets 32 may be formed. In a water cooled engine these may be closed passages and included in the circulatory system.

5 Ignition of the charge is effected in the usual way with a spark plug, the electrodes of which are located in a recess or bay 33 connected with the chamber 25. An exhaust valve 34 is provided, which opens from a similar bay 35. Operating mechanism for this valve is not shown, but it is understood that the valve may be operated by the usual mechanism. The fuel valve, in the form 10 shown, does not require operating mechanism; it is a mere check valve, opened by atmospheric pressure during the suction stroke of the piston, and closed by the spring 29.

15 I attribute the high efficiency of my engine to two principal things. One of these is efficient packing rings in the piston, which has been discussed, and the other is segregation of the products of combustion remaining 20 from the last explosion in the closed end of the compression chamber, that is, near the base of the column 12. I shall now explain how this segregation is effected.

25 Referring to Fig. 1, and assuming that the piston has just completed its exhaust stroke, it is plain that the compression chamber is full of products of combustion remaining from the last explosion, at approximately atmospheric pressure. As the piston moves 30 downward the space vacated by the upper end of the wall 16 of the cup receives old gas from the lower part of the chamber 25, and from the clearance space 26, this old gas being replaced by new fuel mixture entering at 35 the valve 27. By the time the upper end of the cup reaches the lower end of the column all of the old gas is in the upper part of the chamber 25, the lower part of the chamber and the cup itself being filled with explosive mixture which has entered at the valve 27. Having completed its suction stroke, the old 40 gas being still confined to the upper part of the chamber 25, the piston starts its compression stroke. Plainly the old gas in the upper 45 part of the chamber is compressed along with the new gas and as its volume decreases it retreats toward the upper end of the chamber 25, until by the time the piston reaches the upper end of its compression stroke practically 50 all of the old gas will be in the bays 33 and 35, and perhaps there will be a thin layer adjacent the cylinder head 11.

55 While I have called the space 25 a compression chamber, it may as well be called a combustion chamber, for it performs that function too.

60 The presence of the cup is not essential to the process of segregating the old gas in the upper part of the chamber 25. If the cup be removed, and the piston extended so at the end of its stroke it clears the apex of the column only a short distance, the major part of the old gas will be found compressed in the upper part of the chamber 25 at the end of compression stroke.

65 It should be noted that compressing the fuel charge into the thin annular chamber 25 and the very thin space 26 attenuates the charge, spreading it over a large area of heated surface. This produces two desirable results: First, the charge is heated to a high degree, thereby increasing its combustibility, and second, the parts are subjected to less heat per unit of area than in other engines, reducing the difficulty of cooling the engine. 70 75

80 While I have shown what I now deem the preferred embodiment of my invention, it is not to be understood that I limit myself to this structure, as modifications of the structure may be made without departure from the spirit or exceeding the scope of my invention. What I claim as my invention is as follows:

85 1. In an internal combustion engine of the four-stroke-cycle type, a cylinder having a head, a column attached to said head and extending toward the other end of the cylinder, thereby forming an annular compression chamber, and a piston comprising a member having packing rings and a deep cylindrical cup, the bottom of which cup is secured to said member with a layer of heat-insulating material between them, the wall of the cup, which shields from the flame of combustion a zone of the cylinder equal to 90 the altitude of the cup, occupying a large part of the compression chamber at the end of the exhaust stroke of the piston, the column then nearly filling the cup. 95

100 2. In an internal combustion engine of the four-stroke-cycle type, a cylinder having a head, a column attached to said head and extending toward the other end of the cylinder, thereby forming an annular compression chamber, a piston comprising a member having packing rings and a deep cylindrical cup, the bottom of which cup is secured to 105 said member with a layer of heat-insulating material between them, the wall of the cup, which shields from the flame of combustion a zone of the cylinder equal to the altitude of the cup, occupying a large part of the compression chamber at the end of the exhaust stroke of the piston, the column then nearly filling the cup, and means for introducing an 110 explosive mixture between the apex of the column and the bottom of the cup during the suction stroke of the piston, to the end that practically all of the products of combustion remaining from the last explosive stroke 115 shall be confined in the annular part of the combustion chamber and be driven to the closed part thereof during the compression stroke of the piston. 120

125 3. In an internal combustion engine of the four-stroke-cycle type, a cylinder having a head, a column attached to said head and extending toward the other end of the cylinder, thereby forming an annular compression chamber; a piston comprising a member hav- 130

ing packing rings and a deep cylindrical cup, the bottom of the cup being secured to said member with a layer of heat-insulating material between them, the wall of the cup, which shields from the flame of combustion a zone of the cylinder equal to the altitude of the cup, occupying a large part of the combustion chamber at the end of the exhaust stroke of the piston, the column then nearly filling the cup; and means, including a valve in the apex of the column, whereby an explosive mixture is introduced into the cylinder during the suction stroke of the piston.

4. In an internal combustion engine of the four-stroke-cycle type, a cylinder having a head, a column attached to said head and extending toward the other end of the cylinder, thereby forming an annular compression chamber, a piston comprising a member having packing rings and a deep cylindrical cup, the bottom of which cup is secured to said member with a layer of heat-insulating material between them, the wall of the cup, which shields from the flame of combustion a zone of the cylinder equal to the altitude of the cup, occupying a large part of the combustion chamber at the end of the exhaust stroke of the piston, the column then nearly filling the cup; means for introducing an explosive mixture between the bottom of the cup and the apex of the column during the suction stroke of the piston, and a spark plug, the terminals of which reside in a bay situated near the base of the column.

5. In an internal combustion engine of the four-stroke-cycle type, a cylinder having a head, a column attached to said head and extending toward the other end of the cylinder, thereby forming an annular compression chamber, a piston comprising a member having packing rings and a deep cylindrical cup, the bottom of which is secured to said member with a layer of heat-insulating material between them, the wall of the cup, which shields from the flame of combustion a zone of the cylinder equal to the altitude of the cup, occupying a large part of the combustion chamber at the end of the exhaust stroke of the piston, the column then nearly filling the cup; means for introducing an explosive mixture between the bottom of the cup and the apex of the column during the suction stroke of the piston, a spark plug, the terminals of which reside in a bay situated near the base of the column.

6. In an internal combustion engine of the four-stroke-cycle type, a cylinder having a head, a column attached to said head and extending toward the other end of the cylinder, thereby forming an annular compression chamber, a piston which at the end of its inward stroke approaches close to the apex of said column, and means, comprising a valve in the apex of said column, opposite

the piston, whereby an explosive mixture is introduced into the cylinder during the suction stroke of the piston.

7. In an internal combustion engine of the four-stroke-cycle type, a cylinder having a head, a column attached to said head and extending toward the other end of the cylinder, thereby forming an annular compression chamber, a piston which at the end of its inward stroke approaches close to the apex of said column, and means for introducing an explosive mixture between the piston and the apex of the column.

8. In an internal combustion engine, a cylinder having a head, a column of cylindrical form attached to said head and extending toward the other end of the cylinder, thereby forming an annular compression chamber, a piston comprising a deep cup, the side wall of which enters said chamber on the compression stroke of the piston, the bottom of the cup approaching close to the apex of the column at the end of the stroke, thereby driving the major part of the compressed charge into said annular chamber, and means for introducing an explosive mixture at the apex of the column on the suction stroke of the piston.

9. In an internal combustion engine, a cylinder having a head, a column of cylindrical form attached to said head and extending toward the other end of the cylinder, thereby forming an annular compression chamber, a piston comprising a deep cup, the side wall of which enters said chamber on the compression stroke of the piston, the bottom of the cup approaching close to the apex of the column at the end of the stroke, thereby driving the major part of the compressed charge into said annular chamber, means for introducing an explosive mixture at the apex of the column on the suction stroke of the piston, and means near the closed end of the compression chamber for igniting the charge.

10. In an internal combustion engine, a cylinder having a head, a column of cylindrical form attached to said head and extending toward the other end of the cylinder, thereby forming an annular compression chamber, a piston comprising a deep cup, the side wall of which enters said chamber on the compression stroke of the piston, the bottom of the cup approaching close to the apex of the column at the end of the stroke, thereby driving the major part of the compressed charge into said annular chamber, means for introducing an explosive mixture at the apex of the column on the suction stroke of the piston, means near the closed end of the compression chamber for igniting the charge, and an exhaust port at the closed end of the compression chamber.

11. In an internal combustion engine, a cylinder having a permanent annular combustion chamber of a depth equal to at least

- one-third of the piston stroke, which, when the fuel charge is most compressed, contains most of the charge, said chamber being of such shape in cross-section that the charge 5 is reduced to a broad, relatively thin body.
12. In an internal combustion engine, a cylinder having an annular combustion chamber which, when the fuel charge is most compressed, contains most of the charge, said 10 chamber being of such shape in cross-section that the charge is reduced to a broad, relatively thin body, and means for igniting the charge at the edge remote from the piston.
13. In an internal combustion engine, a cylinder having an annular combustion chamber which, when the fuel charge is most compressed, contains most of the charge, said 15 chamber being of such shape in cross-section that the charge is reduced to a broad, relatively thin body, and an exhaust port contiguous to the edge of said chamber remote from the piston.
14. In an internal combustion engine, a cylinder having a permanent annular combustion chamber which, when the gaseous content of the cylinder is most compressed, contains most of said content, said chamber being of such shape in cross-section that the content thereof is a broad, relatively thin 20 body.
15. In an internal combustion engine, a cylinder having an annular combustion chamber which, when the gaseous content of the cylinder is most compressed, contains most 25 of said content, said chamber being of such shape in cross-section that the content thereof is a broad, relatively thin body, and means for introducing fuel to said chamber at the edge contiguous to the piston.
16. In an internal combustion engine, a cylinder having a head, a column attached to said head and extending toward the other end of the cylinder, thereby forming an annular combustion chamber, a piston which at the 30 end of its inward stroke approaches close to the apex of said column, and means for introducing fuel between the piston and the apex of the column.
17. In an internal combustion engine, a cylinder having a head, a column attached to said head and extending toward the other end of the cylinder, thereby forming an annular combustion chamber, a piston which at the 35 end of its inward stroke approaches close to the apex of said column, and means for introducing fuel between the piston and the apex of the column.
18. In an internal combustion engine, a cylinder having a head, a column attached to said head and extending toward the other end of the cylinder, thereby forming an annular combustion chamber, a piston which at the 40 end of its inward stroke approaches close to the apex of said column, means for introducing fuel between the piston and the apex of 45 the column, and an exhaust port at the closed end of said combustion chamber.
19. In an internal combustion engine, a cylinder having a head, a column attached to said head and extending toward the other end of the cylinder, thereby forming an annular combustion chamber, a piston which at the 50 end of its inward stroke approaches close to the apex of said column, an exhaust port at the closed end of the combustion chamber, means for introducing an explosive mixture between the piston and the apex of the column, and means for igniting the mixture at a point contiguous to the closed end of the combustion chamber.
20. In an internal combustion engine, a cylinder having an annular chamber wherein a gaseous charge, introduced at substantially atmospheric pressure, is compressed and then ignited, said chamber being of such 55 shape in cross-section that the charge, when compressed, is a broad; relatively thin body.
21. In an internal combustion engine, a cylinder having a permanent combustion chamber of such form and proportions that when the fuel charge is compressed therein it becomes very attenuated, and means for introducing a charge of combustible gaseous mixture to said cylinder at substantially atmospheric pressure and compressing it in 60 the cylinder.
